[57] CLAIM

The ornamental design for a towing vehicle, as shown and described.

DESCRIPTION

FIG. 1 is a front perspective view of a towing vehicle showing my new design;

FIG. 2 is a front elevational view thereof;

FIG. 3 is a top plan view thereof;

FIG. 4 is a rear elevational view thereof;

FIG. 5 is a left side elevational view thereof, the right side elevational view being a mirror image of that shown; and,

FIG. 6 is a left side elevational view thereof, with the vehicle bed in a lowered condition.

FIG. 1

FIG. 2

FIG. 3

FIG. 4

FIG. 5

FIG. 6
